We claim the ornamental design for an eluent plate for a suppressor, as shown and described.

DESCRIPTION

FIG. 1 is a perspective view of an eluent plate for a suppressor.

FIG. 2 is a top plan view thereof, the bottom view being a mirror image thereof;

FIG. 3 is a left side elevation view thereof, the right side being a mirror image thereof; and,

FIG. 4 is a front elevation view thereof, the rear being a mirror image thereof.

The broken lines show portions of an eluent plate for a suppressor that form no part of the claimed design.
